UNITED STATES PATENT OFFICE.

LEMI B. DENTON, OF GRAND RAPIDS, MICHIGAN, ASSIGNOR TO Z. CLARK THWING, OF SAME PLACE.

CASTER-CASE.

SPECIFICATION forming part of Letters Patent No. 594,987, dated December 7, 1897.

Application filed September 22, 1894. Serial No. 523,822. (No model.)

To all whom it may concern:

Be it known that I, LEMI B. DENTON, a citizen of the United States, residing at Grand Rapids, in the county of Kent and State of Michigan, have invented certain new and useful Improvements in Caster-Cases, of which the following is a specification.

My invention relates to improvements in cases for the support of furniture-casters; and its objects are, first, to provide a case that will support any ordinary furniture-caster and avert the danger of its falling out when the leg of the article to which it is attached is raised from the floor, and, second, to provide a case adapted to receive and support any ordinary caster, from which the caster may be easily removed when desired. I attain these objects by the mechanism illustrated in the accompanying drawings, in

20 which—

Figure 1 is a vertical section of the lower end of a piece of furniture with my case, also in section, in place and a caster inserted; and Fig. 2 is an elevation of the case alone.

25 Fig. 3 is for a caster-shank.

Similar letters refer to similar parts throughout the several views.

This case is designed as an improvement upon the caster attachment secured to me by Letters Patent No. 525,806, issued September 30 11, 1894, and averts the danger of breaking the caster-shank at the bottom of the slit and also averts the necessity of procuring a special caster to supply the place of a broken one.

35 My case may be made either of malleable casting or of steel plate and may be made short enough to be drawn from a single piece of steel plate and still be of sufficient length to support any ordinary caster, which, though 40 very desirable, is not attainable with any other caster-case now manufactured.

In lieu of splitting the caster-shank, as in my previous appliance hereinbefore referred to, I split the upper end of the case, as at B', a short distance down from the top, so that it may be sprung open to admit the ball C', at the upper end of the caster-shank, to pass through easily, and close sufficiently to prevent it from dropping out without a slight 45 amount of pulling at the lower end. This

slot or split may be straight and of any convenient width; but I prefer to have the lower end a little wider than the upper end, as it greatly facilitates the springing properties of the sides, though to make the upper end 55 widest, as shown in Fig. 3, will greatly lessen the difficulty of molding the cases when making them of malleable iron. The body of the case from the lower end of the slot to the track-plate is made solid, as shown in Fig. 2, 60 so that there can be no danger of the sides being forced out of place and lap by each other when being forced into the end of the table or bedstead leg, as is the case with certain other cases of similar construction now 65 in use. The solid body also enables me to fit them into the timber very tightly, thus avert- 70 ing the danger of their becoming loose and falling out. In order to render this form of case available, it is necessary to provide for 75 room in the receiving-hole A' in the leg A for the free opening and closing of the end of the case when the caster-shank is inserted, and for this purpose I make the upper end of the case B from the bottom of the slot B' 75 to the end somewhat smaller than the body of the case, so that it may open freely without coming in contact with the timber of the leg. The upper end of the case is left open. The caster C is inserted in the usual manner, 80 as in Fig. 1.

Having thus fully described my invention, what I claim as new, and desire to secure by Letters Patent, is—

In a case for furniture-casters, a solid body 85 extending up for a distance from the track-plate, the upper end contracted or made smaller and slotted down to the line of contraction so that it can be made to spring apart, and the end left open so that the bulbous end of a caster-stem may be forced through and supported by resting upon the end of the case, substantially as and for the purpose set forth.

Signed at Grand Rapids, Michigan, September 19, 1894.

LEMI B. DENTON.

In presence of—

F. L. STEWART,

I. J. CILLEY.
